UNITED STATES PATENT OFFICE.

DANIEL KELLY, OF SLATERSVILLE, RHODE ISLAND.

IMPROVEMENT IN UMBRELLAS.

Specification forming part of Letters Patent No. 57,151, dated August 14, 1866.

To all whom it may concern:

Be it known that I, DANIEL KELLY, of Slatersville, Providence county, and State of Rhode Island, have invented a new and Improved Folding Umbrella; and I do hereby declare that the following is a full, clear, and exact description thereof, which will enable others skilled in the art to make and use the same, reference being had to the accompanying drawings, forming part of this specification, in which—

Figure 1 represents a sectional elevation of this invention when unfolded. Fig. 2 is a detached view of one of the braces and ribs in a larger scale than the previous figure. Fig. 3 is a sectional elevation of the umbrella when folded.

Similar letters of reference indicate like parts.

This invention relates to an umbrella the ribs of which are made in two parts, which are made to slide one on the other, and which are provided with a spring-catch in such a manner that when the ribs are extended to their full length they are rendered rigid by their catches, and an umbrella is obtained which can be readily reduced to a small compass.

A represents the stick of my umbrella, which is made in two parts that are connected by a screw-thread or in any other suitable manner, so that they can be united to form one stick of the proper length, as shown in Fig. 1, or that they can be taken apart, as shown in Fig. 3. Said stick forms the guide for the runner *a*, from which extend the braces *b*, which connect the ribs *B*. These ribs, instead of being made in one piece, as usual, are made in

two parts, *c c'*, each part being provided at its end with a flange, *d* or *d'*, and these flanges are perforated to admit the parts *c c'* of the ribs, the parts *c'* passing through the flanges *d*, and parts *c* through the flanges *d'*. The flanges *d'* project on both sides beyond the parts *c'*, and to their inner ends are hinged the braces *b*, and from said flanges extend the spring-catches *e*, which are so arranged that when the ribs are extended to their full length they (the catches) drop over the flanges *d* and render the ribs rigid.

The covering of the umbrella is fastened to the ribs in the ordinary manner, and when the ribs are contracted said covering forms an annular bag, which can be easily folded up smooth against the body of the umbrella.

By means of the flanges *d d'* and catches *e* the ribs, when extended, are strengthened rather than weakened, and a folding umbrella is obtained which is superior in strength to an ordinary umbrella, and which can be readily reduced to such a length that it can be conveniently packed in a trunk.

Before folding the umbrella it is necessary to release each spring-catch separately, so that the ribs can be contracted.

What I claim as new, and desire to secure by Letters Patent, is—

The flanges *d* and *d'* and spring-catches *e*, in combination with the two parts *c c'* of the ribs of an umbrella, substantially as and for the purpose set forth.

DANIEL KELLY.
